UNITED STATES PATENT OFFICE.

HARRY G. HAMILTON, OF YOUNGSTOWN, OHIO.

DESIGN FOR AN ARTIFICIAL BAIT.

55,462.

Specification for Design. Patented June 15, 1920.

Application filed July 23, 1919. Serial No. 312,865. Term of patent 7 years.

To all whom it may concern:

Be it known that I, HARRY G. HAMILTON, a citizen of the United States, residing at Youngstown, in the county of Mahoning and State of Ohio, have invented a new, original, and ornamental Design for Artificial Bait, of which the following is a specification, reference being had to the accompanying drawings, forming a part thereof.

Figure 1 is a top plan view of my improved design.

Fig. 2 is a side elevation.

Fig. 3 is a bottom plan view.

I claim:

The ornamental design for an artificial bait as shown.

In witness that I claim the foregoing I have hereunto subscribed my name this 22d day of July 1919.

HARRY G. HAMILTON.
